(57) **CLAIM**

The ornamental design for a plumbing fixture, as shown and described.

DESCRIPTION

In a preferred embodiment, the nature of this product is as a plumbing fixture, preferably a kitchen sink or portion thereof.

FIG. 1 is a right, top, front perspective view of an embodiment of my new design in the form of a deck for a sink; FIG. 2 is a top plan view thereof;

FIG. 3 is a front elevational view thereof, the rear elevational view thereof being a mirror image of the front view shown; FIG. 4 is a right side elevational view thereof, the left side elevational view thereof being a mirror image of the right side shown;

FIG. 5 is a bottom plan view thereof; and,

FIG. 6 is a partial sectional view taken along line 6—6 of FIG. 2.

The broken line representations of underside deck structure in FIGS. 1 and 5, and a basin in FIGS. 1-5 are for the purpose of illustration only, and form no part of the claimed design.
